Primary Examiner — Cynthia Ramirez*Assistant Examiner* — Gino Colan(74) *Attorney, Agent, or Firm* — Taylor English Duma LLP(57) **CLAIM**

We claim the ornamental design for a modular hydrant, as shown and described.

DESCRIPTION

FIG. 1 is a perspective view of a modular hydrant showing our new design.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof; and,

FIG. 7 is a bottom plan view thereof.

The broken lines shown in the figures are for the purpose of illustrating portions of the modular hydrant and form no part of the claimed design.
